UNITED STATES PATENT OFFICE.

JOHN M. HARTMAN, OF PHILADELPHIA, PENNSYLVANIA.

HOT-BLAST STOVE.

SPECIFICATION forming part of Letters Patent No. 254,131, dated February 28, 1882.

Application filed November 10, 1880. (No model.)

To all whom it may concern:

Be it known that I, JOHN M. HARTMAN, a citizen of the United States, residing at Philadelphia, State of Pennsylvania, have invented 5 new and useful Improvements in Hot-Blast Stoves, of which the following is a specification.

The object of this invention is improved means for heating air or gas.

10 The invention consists in the construction and improvements hereinafter enumerated: first, in the construction of the foundation supporting the stoves; second, in the method of cleaning the stoves; third, operating the valves 15 of the stoves with pistons operated by air, steam, or water; fourth, combining the valves, nozzles, and inlets in one casing; fifth, inducing a circulation of water through the cooling-passages of the valves by suction. I attain 20 these objects by apparatus illustrated in the drawings, in which—

Figure 1 shows plan of new foundation, stoves, and pipes. Fig. 2 shows end elevation of stoves and pipes and the foundation in section. Fig. 3 shows a vertical section of stoves with the passages and combustion-chamber. Fig. 4 shows a horizontal section of passages and combustion-chamber. Figs. 5, 6, 7 show plugs or stoppers for the regenerator-openings. 25 Fig. 8 shows elevation of compound nozzles and valves and suction apparatus. Fig. 9 shows plan of compound nozzles and valves and suction apparatus.

Similar letters refer to similar parts throughout the several views.

In operating regenerative stoves the gas to heat them is admitted to the combustion-chamber C, Fig. 3, through the valve K, Figs. 1 and 8, and the air to burn the gas is admitted through 40 the door F, Fig. 8. The products of combustion then pass up the chamber C, down through the regenerator-passages D D D, Fig. 4, and escape at the chimney-valve A'. After the stove is heated up the valves A' K F are closed 45 and the hot-blast valve K' and the cold-blast valve E are opened, which admits air to the stove and thence to the furnace.

Heretofore regenerative stoves have had their flues conveying the gas to and from the 50 stoves built in the foundation outside or be-

yond the outer line of the stoves, which makes a wide, costly foundation. To overcome this I place the flues B B', Fig. 2, under the stoves and lessen the width of the foundation. By this means the walls forming the flues support 55 the stoves and convey the gas also. I am aware that flues have been built in foundations under coke-ovens.

The gas used to heat the stoves is freighted with ashes, which collect on the sides of the 60 passages D D D and choke them. Owing to the slowness of the current of gas through the passages D D D, the gas-ashes collect rapidly and require frequent stoppages for cleaning them. Each passage D D D is independent 65 and surrounded on all sides by continuous brick-work, each brick forming part of four separate passages, which gives the greatest possible heating-surface in the least space.

Cleaning the passages D D D of a regenerator with a brush is a slow, difficult process, and in many cases, owing to the smallness of the passages, the brush jams in them and will not pass through. This passage then becomes useless. To clean the stoves by blowing through 70 the whole regenerator at once the current of air passes too slowly to remove the dust. By building the checker-work to form continuous independent passages and stopping off at the top, as shown in Figs. 3 and 4, say, three-fourths of the openings with plugs, as in 75 Figs. 5, 6, and 7, the blast is concentrated and blown through the balance of the openings with sufficient velocity to remove the dust. Then by shifting part of the plugs to the clean 80 holes the air will be blown through the holes the plugs are taken from, which will clean them. By alternately shifting the plugs and blowing the stoves are thoroughly cleaned. Cleaning the stoves by a jet of air blown 85 through a single opening, the pressure of blast is lost or dissipated by the leakages through the walls forming the passages of the regenerator, and cannot be kept concentrated enough to remove the dust. In my method the whole 90 regenerator is filled with blast under pressure, and no escape takes place except through the openings that are not stopped off.

I do not confine myself to a particular form or method of closing the top of the regener- 100

ator while blowing through, as herein described.

I am aware that attempts have been made to clean these stoves by thrusting a pipe in sections down through the regenerator openings, through which pipe a sharp current of blast was blown. Heretofore various devices of chains, drums, sheaves, and screws have been used to operate the valves of regenerative stoves. I prefer to use cylinders with pistons, as at G G', Fig. 8, attached to the valve-disks to operate them. The pipe H, Fig. 1, for supplying the air to these cylinders is attached to the main cold-blast pipe I of the furnace. When the supply of air is cut off from the blast-furnace the pressure of gas in the interior of the furnace forces the gas back through the hot-blast pipe connecting the furnace to the stoves and fills the stoves with gas.

20 This gas, being carbonic oxide and hydrogen, fires, explodes, and destroys the stoves. By using the cylinders G G', Fig. 8, having their pistons V V' attached to the stems or rods X X', and attaching the rods X X' to the valve-disks S S', then connecting the cylinders at T T' with a pipe, H, to the main cold-blast pipe I, as shown, the pistons and valves are raised by the pressure of blast or air when it is put on the furnace. As soon as blast is taken off from the furnace the pressure ceases under the pistons V V', and the pistons, with the valve-disks, drop and close the valves, thereby cutting off the back flow of gas and avoiding explosions. By this arrangement I combine with the valves of a regenerative stove a means of operating them, which also acts automatically and cuts off the back flow of gas. As these valves are operated between the time of throwing blast off and on the furnace, suitable cocks 35 or valves are placed at the bottom of the cylinders and connected in the pipe conveying the air to the cylinders and pistons.

The pistons can be operated by air, steam, or water; but I prefer the air from the blowing-engine.

45 The cold-blast valve E, being horizontal, is operated with a double-acting cylinder, and does not operate when blast is thrown off the furnace.

50 The valve for throwing blast off and on the furnace is placed in the cold-blast pipe I, between the stoves and the blowing-engine.

I am aware that surging-valves have been used in cold-blast pipe, which valves were operated by pistons, as in the patent of H. Davies, 55 113,745, April 13, 1871; but in this case the gas would back into the stoves, as the valves are not placed between the furnace and the stoves.

60 I am also aware that it has been proposed to place the above surging-valves in the hot-blast pipe between the furnace and the stoves; but there being no provision made to cool the valve, it would soon be destroyed by the high 65 heat from the regenerative stove.

I do not broadly claim an automatic valve

for cutting off the back flow of gas from a furnace; neither do I claim a water-cooled valve in combination with a regenerative stove.

I do not confine myself to a certain position of the hot-blast valve K', as it can be made separate and placed nearer the furnace.

Heretofore valves and nozzles for regenerative stoves have been made in separate pieces. This makes extra joints, a greater number of 75 separate attachments to the stove, and increases its cost. To obviate this I combine two or more nozzles and valve bodies or valves, K K', and inlets F P in one casing, as at R, Figs. 8, 9. By this combination three or more 80 separate attachments are made in one piece and a better pipe arrangement is obtained.

In operating regenerative stoves the valves are subjected to an intense heat, and are cooled with an internal circulation of water under 85 pressure to keep them to shape and prevent the leakage of gas or blast. At times these valves crack and leak water into the furnace, which chills the hearth and stops its operation. This water also forms hydrogen gas, 90 which has exploded and caused a large loss of life and property. To obviate this I draw the cooling-water through the pipe J J' W W', Fig. 8, in the valve disks and bodies by putting it in a state of tension or below the atmospheric pressure in the disks and bodies. If a valve cracks with the water in tension, there will be no leak of water into the hot-blast pipe or stove. The pipe Z Z' supplies the valve-disks with water. The pipe W W' passes 100 through the pipe Z Z' over the top of the cylinders, leaving an annular space between the inner and outer pipe, through which the water flows to cool the disks.

The water can be put in tension by a pump, 105 W', or a pipe with a low outlet.

I am aware that the discharge-water pipe of the valves of a regenerative stove has been carried down to the bottom of the stove before discharging the water; but to induce a proper 110 circulation I carry it not less than three feet below the bottom of the stove when pumps are not used.

I claim—

1. In combination with an air-tight regenerative stove, an external foundation having in it the flue B for conveying the unburned gas to the stove and the flue B' for conveying the burned gas to the chimney, the said flues being placed under the stoves, and the 120 connections from the stoves to the flues being external to the stoves.

2. The method of cleaning the passages of a regenerative stove, which consists in stopping or closing part of the passages and discharging a current of compressed air through the remaining passages, whereby the air-blast is concentrated in the open passages and a thorough cleaning is obtained.

3. In combination with a regenerative stove 130 having water-cooled valve-disks S S', the cylinders G G', the pistons V V', the piston-rods

X X', and pipe T T', for operating the valve-disks.

4. In combination with a regenerative stove, a compound nozzle containing the valve-bodies K K' and one or more openings, F P, into the stove.

5. The combination, with the valves and their seats, of a regenerative stove, the valves and

valve-seats being provided with water-circulating passages, an eduction-pipe, and exhausting device, whereby a circulation of water is induced through the said passages by suction.

JOHN M. HARTMAN.
